ATTORNEY

D. B. B. Jr.
WITNESS:

UNITED STATES PATENT OFFICE.

HERMAN F. MIETZ, OF FRANKLINVILLE, NEW JERSEY.

BANJO RESONATOR.

Application filed January 2, 1925. Serial No. 231.

This invention relates to a resonating or amplifier attachment for banjos, and an object of the invention is to provide a resonator or amplifier which is made wholly of wood thereby embodying the well known and definitely established fact that musical sounds are more harmoniously amplified by wood than by any other material, and particularly by metals, which latter have a tendency to add metallic sounds to the notes produced.

Another object of the invention is to provide an amplifier or resonator which is constructed to permit it to be quickly and easily attached to a banjo or detached therefrom.

A further object of the invention is to provide a resonator or amplifier attachment for banjos in which the resonant proclivities of the rim of the banjo are augmented through its engagement with a suitable sound conveying ring or flange which is in turn rigidly connected to a suitable sounding board and in spaced relation to the sounding board.

Other objects of the invention will appear in the following detail description, and in the accompanying drawings wherein:

Figure 1 is a section through the improved resonator showing it attached.

Figure 2 is a top plan of the resonator.

Referring more particularly to the drawings, the improved resonator comprises an annular band 1, which is constructed of wood and preferably of laminated layers of wood, so as to provide the proper strength and permit bending of the band into circular shape. A sounding board 2 is attached to the bottom edge of the band 1 and this sounding board is preferably concavo-convex, with its concave surface disposed upwardly towards the under surface of the banjo, and it is also formed of a plurality of layers of wood, which will permit of attractive appearance in the assembling of the device, as well as eliminate liability of warping.

Arranged in a groove formed adjacent the upper end of the band 1 is a flange or ring 3 which is provided with a plurality of equidistantly spaced sound emitting openings 5 which are circumferentially disposed in close proximity to the inner wall of the annular band as suggested in Figure 2 of the drawings. The top edge of the annular band is provided with a substantially rectangular cut away portion 7 which is to provide a

clearance space for the arm portion 8 of the banjo which is indicated in dotted lines in Figure 1 and by the reference letter A. The inner free edge of the flange 3 terminates in a depending annular rim 6 of a slightly greater width than the thickness of the flange 3, and said rim 6 is provided with diagonally disposed slots 6' through which pass the horizontal portions 9 of securing clamps. These securing clamps have upstanding portions 10 which are adapted to engage the inner wall of the banjo frame as suggested in Figure 1, and also formed with said clamps are depending ears 11 which are provided with threaded openings 12 for threadedly receiving the clamp actuating screw bolts 13. The screw bolts 13 extend through openings formed in the band 1 and have their heads counter-sunk in recesses 75 reinforced by metal cups 15 to prevent undue wear upon the band 1 by the heads of said bolts, as will be obvious.

In attaching the resonator or amplifier to a banjo, the banjo is placed upon the pads 16 secured on the upper surface of the flange 3, and the screw bolts 13 are actuated so that the banjo is tightly clamped in position by means of the upstanding engaging portions 10 of the clamps which act to securely hold the attachment to the banjo, with a view of forming a solid rigid unit thereby, as will be readily apparent.

The resonating proclivities of the banjo are augmented and changes are made in the sounds of the banjo when the attachment which forms the subject matter of the present invention is secured thereto. Posts or pins 4 are disposed between the sounding board 2 and the flange 3 and act as a supporting means for the flange as will be readily apparent and the clamps cooperate with each other for rigidly securing the attachment and banjo in the manner as suggested.

It is, of course, to be understood, that the invention may be constructed in various other manners and the parts associated in different relations, and therefore, I do not desire to be limited in any manner, except as set forth in the claims hereunto appended.

What I claim is:

1. A banjo attachment constructed entirely of laminated wood and comprising an annular band, a sounding board secured to one edge of said band and having its inner surface concaved, an annular flange secured

to said band adjacent the opposite edge thereof and being provided with a plurality of equidistantly spaced sound openings, a supporting means for said flange positioned 5 between the flange and sounding board, and a plurality of clamping members carried by said annular band, positioned inwardly of the inner edge of the flange.

2. A laminated wood amplifying attachment for banjos comprising an annular band, 10 a concavo-convex sounding board secured to one edge of said band with its concaved surface disposed inwardly, an inwardly extending annular flange secured to said band 15 adjacent the opposite edge thereof and being provided with a plurality of spaced circumferentially arranged sound openings, a plurality of spaced upright posts connecting said sounding board and flange for supporting the latter in operative position and 20 means carried by said annular band for threadedly receiving a plurality of clamping members for detachably connecting the attachment to a banjo.

3. A laminated wood amplifying attachment for banjos, comprising an annular band, a concavo-convex sounding board attached to one edge of said band with its concaved surface disposed inwardly, an inwardly extending annular flange positioned 25 in a groove formed within and adjacent the upper end of said band and being provided with a plurality of openings disposed adjacent the outer edge thereof, a plurality of

spaced upright posts disposed between said 35 sounding board and flange for supporting the latter, headed bolts passing through the annular band and clamping members threadedly secured to said bolts for engaging a banjo and clamping the attachment thereto 40 to form a solid unit.

4. An amplifier attachment for banjos, comprising an annular band of laminated wood having recesses therein, a sounding board secured to one edge of said band, an 45 inwardly extending annular flange secured adjacent the opposite edge thereof and being provided with a plurality of circumferentially arranged openings disposed adjacent the outer edge thereof, a depending 50 rim formed on the inner edge of said flange, and being provided with a plurality of spaced diagonally arranged openings, posts disposed between the sounding board and flange for supporting the latter in spaced relation with the board, cups arranged in the 55 said recesses, headed bolts arranged in the cups and passing through the annular band, clamping elements including depending ears threadedly secured to said bolts and 60 standing portions also included in said clamping elements for engaging a banjo for clamping the latter with the attachment in a manner to provide a rigid unit as and for the purpose specified.

In testimony whereof I affix my signature.

HERMAN F. MIETZ.
